UNITED STATES PATENT OFFICE

AMOS P. STEINER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA

AUTOMATIC GRINDING MACHINE

Application filed August 14, 1925. Serial No. 50,316.

My said invention relates to an automatic grinding machine and it is an object of the same to grind automatically small duplicate articles such as piston pins or other articles, which are made in large quantities, eliminating the usual handling operations by performing them automatically in the machine, allowing the operator time to run several machines.

Another object is to provide means whereby the various movements of different parts of the machine are performed hydraulically.

Another object is to provide means for urging the work toward a stationary grinding wheel to produce a feeding movement as the grinding operation proceeds.

Another object is to provide means whereby the wheel is given a lateral reciprocating movement to remove any grinding marks caused by the wheel.

Another object is to provide a pump to supply pressure fluid to the traversing motor, the work feeding motor, the work chucking cylinder, and the tailstock operating mechanism.

Another object is to provide a reservoir, in which to store surplus pressure for use at a time when the motors require the greatest amount of pressure fluid.

Referring to the accompanying drawings which are made a part hereof and on which similar reference characters indicate similar parts,

Figure 1 is a front elevation of my machine in a preferred embodiment thereof,

Figure 21, a vertical section through the feeding means and magazine showing the work out of grinding position,

Figure 22, a section through the feeding means showing the work carrier in retracted position.

In the drawings reference character 25, 80 (Figs. 1 and 2) indicates a frame of any desirable form for supporting the various operating elements as hereinafter described. A wheel base 26 mounted on said frame supports a grinding wheel 27 and is mounted 85 upon suitable guides for adjusting the wheel toward and away from the work by the manually-operated feed wheel 28 all in a manner well known to those familiar with the construction of grinding machines.

The main drive shaft 29 is located in the base of the machine and delivers power to the wheel spindle 30 through a belt 31. Said wheel spindle has formed thereon at one end (Figs. 3, 4, 5, 6) a worm thread 32 engaging 5 with a worm wheel 33. The large ratio between said worm and wheel causes the rapidly revolving spindle 30 to revolve the worm wheel with a relatively slow motion. The worm wheel 33 is loosely journaled upon a shaft 34 between a collar 35 and a cone faced clutch member 36 which member may be forced into engagement with a corresponding clutch face on the worm wheel by means of a screw 37 abutting at one end against a pin 38 carried by clutch member 36 and provided at the other end with a button or hand wheel 39. A collar 40 on the screw coacts with the cap 40' to prevent accidental removal of the screw and the screw has 10 threaded engagement in a bore in the shaft 34.

A pair of eccentrics 41 on the shaft 34 engage yokes 42 pivoted to studs 43 on the housing 44, the upper end of each yoke being connected by a link 45 to a collar 46 which is loosely mounted on a reduced portion of the wheel spindle 30 and is held against movement lengthwise of the shaft by hardened 20 steel thrust collars 47 which are located at opposite sides of the collar 46 between a shoulder at one end of said reduced portion and a nut 48 engaging a threaded part of the shaft which threaded part is of still smaller size and said nut being adjustable for wear.

In operation the revolving spindle 30 slowly turns the shaft 34 and the eccentrics 41 rock the yokes 42 and through the links 45 and the collar 46 they cause the wheel spindle and the wheel to traverse slowly back and forth to eliminate grinding marks caused by the wheel standing in one position relatively to the length of the work. To render this device inoperative the clutch is disconnected by turning the button 39 to back off the 30 screw 37.

A pump 49 is located in the base of the machine above a reservoir formed in said base which reservoir serves as a supply for the oil or other liquid for operating the various mechanisms hereinafter described. The pump, which is driven by a chain 50 from the main drive shaft 29, receives the oil from the tank through a suction pipe 51 and delivers it through a pipe 52 with a rigid branch 53 and flexible branches 54 and 55 to various mechanisms hereinafter described.

The traversing motor 56 and its connections to the work carriage are similar to the parts described in detail in my co-pending application No. 721,292, filed June 20, 1924 which matured into U. S. Patent No. 1,662,546, issued Mar. 13, 1928, and therefore it will be but briefly described 60 here as operating the gear 57 for traversing

the work carriage back and forth. The purpose of such traverse in this application is mainly for dressing the grinding wheel, but it may be used to grind longer work than the width of the wheel and the short reciprocation of the wheel spindle will cover. The throttle valve 56', the operating levers 57' and 58' and the work speed change 82 are also similar to the construction described in detail in the above named application, and will therefore be but briefly referred to here.

A work carriage 58 is mounted for reciprocation upon guides on the upper part of the frame 25, said carriage bearing a rack 59 movable by the gear wheel 57 for traversing in the direction of its length. A swivel table 60, (Figs. 7 and 13) is mounted upon said carriage and is trunnioned at 61 for swivelling to correct any mis-alignment of the work-supporting means. Mounted upon the swivel table 60 (Figs. 7 and 13) is a magazine bracket 62 which bears the work carrying heads. Said bracket is mounted to swing about a horizontal axis, the bracket having two or more depending arms secured to shaft 63 for oscillation therewith in bearings 64 on the swivel table, or being loosely mounted on the shaft to oscillate thereon. The bracket is actuated by a cam 65 on a shaft 66 operating against the rollers 67, which are supported by the shaft 68 (Figs. 10 and 13).

The cams 65 swing the bracket 62, with which the head and tail stocks are integral, together with its trunnion 63 for a feeding movement of the work 70 against the grinding wheel 27 at the proper time in appropriately timed relation with the movements of other parts of the machine as hereinafter described.

The camshaft 66 is driven by an electric motor 71 mounted on a base 72 on the swivel table 60. Sprockets 73 and 74 connected by a sprocket chain 75 are mounted respectively on the motor shaft and on a shaft 76 provided with a worm gear 77 meshing with a worm wheel 78 fast on a shaft 79. Another gear 80 fast on this shaft has teeth engaging those of a gear 81 on the camshaft 66. The base 72 of the motor is hollow and serves as a gear casing for the gearing between the shafts 76 and 66. The operation of the motor 71 thus rotates the camshaft which swings the magazine bracket to impart to the work a feeding movement toward and from the wheel, the downward and outward movement being under the action of gravity which may be augmented by a spring if desired. The motor is driven by any conventional or desirable means.

The drive for the work is transmitted from the main drive shaft 29 to the change speed 125 gearing indicated at 82 by means of a belt 83. Different speeds may be obtained at this point by operating the gear-shifting lever 84 (Fig. 1). Power is transmitted from the change-speed gearing through a sprocket 130

chain indicated at 85 to a sliding shaft 86 provided with sprocket gears 87 and 88 (Fig. 7). A sprocket chain 89 connects sprocket 88 to a sprocket 90 on a shaft 91 journaled at one end in a bearing in the trunnion shaft 63. Another sprocket 92 on this shaft transmits the drive to the headstock spindle 93 by way of a sprocket chain 94 and a sprocket 95 on said spindle. The sprockets 90 and 92 are thus located on the axis of the trunnion shaft 63 so that the swinging action of the bracket 62 during the work feeding movement does not change the sprocket centers and thus interfere with the proper working of the driving sprocket chains. It will be recalled that the headstock 96 and the tailstock 97 are integral with the bracket 62, therefore the distance between sprockets 92 and 95 remains the same at all times and the spindle 93 is driven in a uniform and steady manner while grinding.

The headstock 96 has spaced bearings in which the spindle 93 is rotatably mounted and the work 70 (Figs. 7 and 8) rotates with the spindle, being held on the spindle by the fingers 98 of a chuck 99. Fingers 98 are fulcrumed on pins 100 and are normally held in an open position by springs 101. A cone-shaped plunger 102 operates against the beveled rearward extensions of the fingers 98 and serves, when moved toward the left, to close the fingers and hold them securely in closed position. To compensate for the angular change in position of the fingers as the chuck jaws 103 move inward toward the work or vice versa and to cause said fingers to bear evenly on the cone shaped plunger 102, each finger is provided at its rear end with a hemispherical seat for a hemispherical shoe 104 held by a screw 105 which screw passes loosely through a hole in the finger and permits the block to adjust itself freely so as to bear evenly at all times against the hemispherical surface of its finger. The plunger 102 is connected to a piston 106 of a reciprocatory fluid motor by means of a rod 107. The piston 106 is encased in a cylinder 108 closed at the ends, said cylinder being supplied with fluid under pressure by means of a conduit 109 and ports 110 for closing the chuck. The fluid pressure is exhausted through the same conduit when the chuck is to be opened. The cylinder is closely sealed, and a casing 111 is provided thereabout for catching any oil that leaks out, the casing having a drain opening at 112 whereby such oil may be removed and returned to the main tank or otherwise employed.

It is obvious that the headstock spindle 93 and the cylinder must revolve, while the conduit 109 is stationary. With this end in view a revolving joint is provided between said parts said joint comprising an inner revolving sleeve 113 which screws into the piston 106, an outer casing 114, and a head 115 attached to

the conduit 109 and arranged to compress packing 116 between said head and said outer casing so as to allow no fluid to escape. The pressure of the oil in the fluid pressure system keeps the shoulder on the sleeve 113 against the casing 114 and the nuts 113' restrict the longitudinal movement of the sleeve, but are free enough to allow the same to revolve.

As above indicated the chuck 99 is closed by fluid pressure. For this purpose the pump 49 supplies pressure fluid through the pipes 52 and 55 to the balanced piston valve 117 (Figs. 16—17). The piston 118 is operated in one direction by a cam 119 on the cam shaft 66 admitting liquid from the pipe 55 through the port 120 and the pipe 109 to the cylinder 108 (Fig. 7) against the piston 106 which pulls back the cone plunger 102 causing the jaws 103 to grip the work 70.

For opening the chuck the following mechanism is provided: The piston 118 is biased to move in the direction opposite to that for admitting pressure to close the chuck by means of a spring 121 which forces the head 122 of the piston against the free end of a rocker 123 pivoted at 124 on a fixed part of the machine, and the piston is so moved when the cam 119 reaches the point in its rotation where the depression 125 in the cam is immediately in the path of the head 122 of the piston. At such time the piston will take the position shown in Figures 16 and 17 in which the oil will be exhausted through the rigid pipe 126 and flexible pipe 127 to the tank by means of spring 128 acting through rod 107 upon piston 106 as the spring 128 (Fig. 8) retracts the cone plunger 102 permitting springs 101 to swing the clutch fingers 98 in the direction for opening the chuck jaws thereby releasing the work 70.

The tailstock 97 (Fig. 7), being cast integral with the bracket 62 to preserve its alignment with the headstock 96 must have its center operated in synchronism with the headstock chuck, so that when the work 70 is released by the fingers 98 the tailstock center 129 will recede simultaneously to release said work.

For actuating the tailstock center to perform such operation the following fluid-pressure-operated mechanism is provided, reference being had to Figures 1, 7, 18 and 19:

An upwardly extending arm 130 is secured on a rearward extension of the tailstock spindle and is restricted in its movement by collars 131, said arm being connected at its upper end to the rod 132 of a piston 133 by collars 134. The piston operates in a cylinder formed in a casing 135 which may be unitary and accommodates both the piston and a controlling valve therefor hereinafter described. The cylinder receives pressure fluid by way of pipes 54, 136 and 137 which pressure fluid moves the piston to withdraw the tailstock 130

center 129 from the work, the piston and its coating parts forming a reciprocatory fluid motor for positioning the tailstock spindle.

The combined cylinder and valve casing 135 carries a balanced piston valve 139 for controlling the operating mechanism of the tailstock spindle. It is operated in one direction by a lever 140 for admitting pressure fluid from the pipe 137 (Figs. 1, 13 and 19) to the cylinder to move the piston 138 and thus retract the center 129 to release the work. Said valve 139 is operated in the opposite direction by a spring 141 for exhausting the pressure fluid through a pipe 142 and allowing the foot stock center to be returned by a spring 143 which bears at one end against a plug 144 fixed to the tailstock and at the other against a shoulder on spindle 145, thereby engaging and holding the work. The lever 140 is operated by a cam 146 on the cam shaft 66 which is set so as to operate in synchronism with the cam 119 at the other end of said shaft which operates the headstock chuck.

A magazine 147 (Figs. 20-21-22) for the work is bolted on the bracket 62, which bracket fulcrums on the shaft 68 and the magazine swings with the bracket in the feeding movement of the same by the cam 65.

A bar 148 (Figs. 11-20-21) is slidably mounted in the bracket 62. A rack 149 is slidably mounted under the bar 148 and has lost motion with respect to said bar, the lost motion being limited by engagement of the ends of the rack with abutments in the form of spaced blocks 150 and 151 located respectively at the front and rear ends of the slideable bar, to which they are secured by bolts or in any other convenient manner. A work carrier 152 is pivotally attached to the front end of the slideable bar 148 by means of pivot pins 153.

A block 150' (Fig. 12) is secured to the under side of the work-carrier 152 adjacent to the block 150. As the rack 149 moves forward its end strikes the block 150' in the first part of its movement and moves the work-carrier from the pivoted position of Figure 22 into the solid-line position of Fig. 21. Thereupon the rack strikes the block 150 on the bar 148 and carries the complete mechanism with the work into the dotted-line position of Fig. 21. A segment gear 154 engages the rack 149 and is adjustably mounted on the shaft 155 by means of a bolt 156 (Fig. 11) having its head in an undercut groove 157 in the gear. A nut 158 locks the bolt in adjusted position, and the free end of the bolt engages a hole in a collar 159 secured to the shaft in any suitable manner. Adjustment of the segment gear about the shaft positions the rack and the work carrier relatively to the work center 129 and the chuck 99.

The shaft 155 is the drive shaft of an oscillating hydraulic motor (Figs. 11, 13, 14 and 15) which operates the automatic feed-

ing mechanism by which the work is fed from the magazine to the grinding means and then out of the machine. This motor comprises a casing 160, a cover 161, a blade hub 162, a blade 163 and means arranged to alternately admit pressure fluid on either side of the blade 163 for oscillating the shaft 155 and the gear segment 154.

The controlling means for the magazine operating motor includes a balanced piston valve 164 (Figs. 13 and 15) housed in the motor casing 160, said valve being movable in one direction by the abutment 166 having a stem 167 adjustably mounted in a boss formed on the bottom of a container 175 on the swivel table 60 and in the contrary direction by the spring 165.

As the bracket 62 is lowered by the cams 65 the valve 164 is opened by bringing the roller 168 against the abutment 166 causing said valve to move upward so as to allow fluid pressure to enter by way of the pipe 170 and the port 169 revolving the blade 163 in a clockwise direction in Figure 13 causing the magazine attachment to feed a new piece of work in to the work centers. At this time the fluid at the opposite side of the blade escapes by way of the port 169' to the exhaust pipe 172.

The cams on the camshaft 66 are so timed that the cam 146 (Figs. 10 and 18), while the parts are in this position, operates the lever 140 to let off the pressure fluid from the valve 139 and allow piston 138 to return under pressure of spring 143 (Figs. 10-19) causing the tailstock center 129 (Fig. 7) to engage the work and push it into the grasp of the jaws on chuck fingers 98, whereupon the cam 119 operates through the headstock chuck, as hereinbefore described and causes the jaws 103 to grip the head of the work 70.

After depositing the work between the centers the cams 65 revolving, raise the bracket 62 and the valve 164 travels by the expansion of the spring 165 until the port 169' is open to the feed pipe 170 and the port 169 is open to the exhaust pipe 172 whereupon the blade 163 is caused to revolve in a counterclockwise direction, which causes the segment gear 154 to retract the rack 149 and the bar 148, whereupon the work carrier 152 being no longer supported by pressure of the rack 149 against the abutment 150 drops down into the position shown in Fig. 22 clearing the work and returning to position under the magazine as shown in Fig. 20.

The space between the end of the rack and the rear block 151 is provided so that during the first part of the retracting movement of the rack 149 it moves over against said rear block out of contact with the front block 150 and the work carrier 152. This allows said carrier room to drop away from the work as shown in Figure 22. Also on the forward

movement the rack 149 moves away from the block 151 and up against the block 152 holding it up in the position shown in Figure 21 for carrying the work over to the head and tail stocks. After the work-carrier has been moved back beneath the magazine the bracket 62 is still being swung upward by reason of the contour of cams 65 and thus a feeding movement is imparted to the work during the grinding operation.

A reservoir 173 (Fig. 1) is mounted on the feed pipe 136 and is connected by pipe 137 to the reciprocating motor for the tail-stock center 129. A check valve 174 is provided at the bottom of the reservoir 173 which allows pressure fluid to enter the reservoir and build up pressure, but restricts it from returning when the pressure drops.

The various motors are so timed in their operation as to act nearly at the same time and, in fact, so near together that the pressure in the feed line drops to some extent at certain times on account of the excessive demands thereon. By feeding the tail stock operating cylinder 135 from this reservoir 173, thus making use of the high pressure which is generated and stored while the motors are not feeding, a much smaller pump 49 can be used than would otherwise be required with a consequent considerable saving in power.

For the convenience of the workman, a container 175 is attached to the swivel table 60. This container should be large enough to hold a number of articles corresponding to a charge of the magazine, but may be of any desirable size. A chute 176 (Figs. 1 and 13) leads from a point beneath the work-ejecting position of the machine to the container 175.

In the operation of my device a number of articles such as push rods for automobile valves or other similar small objects are placed in the magazine 147, (Figs. 1, 15, 20, 21 and 22). While the rollers 67 ride on the low part of cams 65 the work chuck 99 is opened by the spring 128, the shaft 66 being now in the position illustrated in Figure 17 to remove the fluid pressure from the piston 106. At the same time the tailstock center 129 is drawn back by the admission of fluid to the cylinder 135 thus releasing the finished article which passes down the chute 176 to the container 175 where it may remain until removed by a workman. In the meantime fluid is admitted to the motor 160 and causes it to move the bar 148 forward to the position shown in dotted lines in Fig. 21 carrying the work into line with the work centers whereupon fluid pressure is cut off from the cylinder 135 and admitted to the cylinder 108 and the tailstock center is moved forward by the spring 148, the headstock chuck being closed by fluid pressure from pipe 109 as the

head of the work is carried into position between the jaws 103.

The cams 65 on the shaft 66 now begin to raise the rollers 67 swinging the bracket 62 and therefore the work toward the grinding wheel 27. During the upward swing of the bracket the valve of motor 160 was reversed by spring 165 to admit pressure to the opposite side of the motor and therefore the rack 149 is now retracted permitting the workholder 152 to fall into the position indicated in Figure 22 and moving the bar 148 and the workholder from the dotted line position of Figure 21 to a position under the magazine substantially as indicated in full lines in said figure. By reason of the form of the cams 65 the swinging bracket 62 continues to be moved upward actuated by the gradual rise of the cams as indicated in Fig. 20 thus affording a feeding movement of the work toward the grinding wheel so as to make the finished work of predetermined size.

The shaft 66 and cams 65 continue to rotate and at the time that the work is finished the rollers 67 pass to the low part of the cam 69 whereupon the cam 119 attains the position shown in Figure 17 so as to release the headstock chuck and the cam 146 assumes the position indicated in Fig. 1 to admit pressure to the cylinder 135 and withdraw the tailstock center to release the work thus completing the cycle of operations.

The operation of the machine may be varied for grinding either short or long work. By opening the valve 56' to admit fluid to the motor 56 the work carriage will be reciprocated and the reversing lever 58' will be operated to give reversing movement to the carriage through said motor. This movement may be of any length within the capacity of the machine. In case short work is to be ground where the reciprocation of the carriage is not necessary the valve 56' will be closed putting the motor 56 out of action. At this time it is desirable to reciprocate the wheel spindle 30 with the wheel to prevent grinding marks from appearing on the finished work due to minute irregularities in the wheel. For this purpose the mechanism of Figs. 4 and 5 is provided and it will be seen that by manipulation of hand wheel 39 the shaft and wheel may be caused to reciprocate slowly through a relatively short distance. By releasing the clutch member 36 the wheel can stand still and this is preferable when the machine is used for grinding long work and the work carriage is reciprocated.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent is:

1. A grinding machine comprising an abrading device, a headstock, a tailstock, a worktable, a pivoted bracket thereon carrying the headstock and tailstock, workholding means on the headstock and tailstock, a magazine, means for oscillating the bracket to feed the workholding means toward and from the abrading means, means for bringing the workholding means and the abrading device into and out of operative relation, means for replenishing the work while said devices are out of operative relation including a fluid motor on the bracket, a valve controlling the entry of pressure fluid, a fixed abutment for moving said valve during the oscillation of the bracket to admit fluid to the motor, a camshaft on the carriage, cams on the camshaft for oscillating said bracket, and a motor on the carriage for driving said camshaft.

2. In a grinding machine, a wheel, a headstock, a tailstock, workholding devices on the headstock and tailstock, fluid motors operating said devices, a magazine, means for feeding articles from the magazine to the workholding devices including a fluid motor, valves controlling the entry of fluid to each of said motors, a camshaft, connections from the camshaft for operating each of said valves, a bracket supporting the headstock the tailstock and the magazine said bracket being pivoted to move the work toward and from the wheel, and cams on said camshaft for moving the bracket on its pivot, substantially as set forth.

3. A grinding machine including a wheel, workholding means, a magazine, means for imparting feeding movement to the workholding means, a bar reciprocating between the magazine and the workholding means, a pivoted lip on the bar, a rack having lost motion connection to the bar to raise the lip on movement toward the rear of the machine and drop it on reverse movement, a pinion engaging the rack, a shaft carrying the pinion, a blade on the shaft forming the rotor of a fluid motor, and a fixed casing about said shaft and blade, substantially as set forth.

4. A grinding machine comprising a grinding wheel, work holding means, means to supply work to the workholding means comprising sliding members movable with respect to each other, a positive stop on one of said members, a work carrying device pivoted on said member, said stop and said device being adapted to engage a second sliding member, lost motion between said members limited by said stop and said work carrying devices, rack teeth on said second member, a gear segment engaging said rack, means for rotating said gear segment accu-

rately through a distance sufficient to place the work in grinding position, and means whereby rotation of said segment in one direction holds said work device in operative position and rotation in the opposite direction allows said device to return to inoperative position, substantially as set forth.

5. A grinding machine comprising a grinding wheel, workholding means, means to supply work to the workholding means comprising sliding members movable with respect to each other, a positive stop on one of said members, a work carrying device pivoted to said member, said stop and said device being adapted to engage a second sliding member, lost motion between said members limited by said stop and said work carrying device, rack teeth on said second member, a gear segment engaging said rack, means for rotating said gear segment accurately through a distance sufficient to place the work in grinding position, and means whereby rotation of said segment in one direction places the work in grinding position and rotation in the opposite direction releases said work to the work holding fixture, substantially as set forth.

In witness whereof, I have hereunto set my hand at Waynesboro, Pennsylvania, this thirty-first day of July, A. D. nineteen hundred and twenty-five.

AMOS P. STEINER.
